tion of Maine

Application January 10, 1935, Serial No. 54,794

To all whom it may concern:

Be it known that I, Nicholas J. Grossman, a citizen of the United States, residing at Lynn, in the county of Essex and State of Massachusetts, have invented a new, original, and ornamental Design for a Shoe, of which the following is a specification, reference being had to the accompanying drawing, forming a part thereof, in which

The figure is a view in perspective of a shoe showing my design, the outline of the heel being conventional and shown in dot and dash lines.

The opposite side of the shoe presents substantially the same appearance as the side shown except that the eyelets, lacing and buckle do not appear.

I claim:

The ornamental design for a shoe substantially as shown and described.

In testimony whereof, I have affixed my signature hereto.
